COMBINED STAND AND PERFUME BOTTLE

Frederick M. Breen, White Plains, N. Y., assignor
to Coty, Inc., New York, N. Y., a corporation of
Delaware

Application September 7, 1949, Serial No. 4,876

Term of patent 14 years

(Cl. D86—10)

To all whom it may concern:

Be it known that I, Frederick M. Breen, a citizen of the United States, residing at White Plains, in the county of Westchester and State of New York, have invented a new, original, and ornamental Design for a Combined Stand and Perfume Bottle, of which the following is a specification, reference being had to the accompanying drawing, forming part thereof.

In the drawing

Fig. 1 is a front elevational view of a combined stand and perfume bottle showing my new design;

Fig. 2 is a side elevational view thereof.

Fig. 3 is a top plan view.

Fig. 4 is a fragmentary side elevational view with the top holder pivoted to permit release of the perfume bottles.

The figures are shown broken away to illustrate the form of the article.

The dominant features of my design reside in the portions shown in full lines.

I claim:

The ornamental design for a combined stand and perfume bottle, as shown and described.

FREDERICK M. BREEN.
